JOHN LANDIN, OF STOCKHOLM, SWEDEN.

RADIOACTIVATING SUBSTANCE.

1,175,533.

Specification of Letters Patent. Patented Mar. 14, 1916.

Application filed January 30, 1914. Serial No. 815,418.

To all whom it may concern:

Be it known that I, JOHN LANDIN, a subject of the King of Sweden, residing at Drottninggatan 40, Stockholm, Sweden, have invented new and useful Improvements in Radioactivating Substances, of which the following is a specification.

The present invention relates to a means for radioactivating liquids, for instance 10 water, or gases, for instance air, by the introduction thereinto of radioactive emanations, especially emanation of radium, from radioactive substances producing emanations, for instance salts of radium, by means 15 of solid or liquid mediums surrounding or embracing said substances, said mediums being not only indifferent with relation to the liquid or gas as well as to the embraced radioactive substance, but having also the 20 property of absorbing emanation from the said substance in their mass, allowing it to pass only through the said mass and yielding it to the liquid or gas when the medium together with the substance producing emanation is introduced into or brought into 25 contact with the latter. The medium in question should thus be capable of readily absorbing emanation from solid radioactive bodies or solutions thereof and should not 30 be soluble in the liquid or destroyable by the gas to be radioactivated. As examples of such mediums suitable for the radioactivation 35 of water for drinking or bathing purposes and of air or oxygen for inhalation there may be mentioned: paraffin, wax, paraffin oil. If a radioactive substance producing emanations is inclosed in or mixed into or surrounded with such a medium, a body ready for direct radio-activation of liquids 40 and gases is obtained which is herein referred to as an activating substance. By activating liquids or gases by means of activating substances obtained in this way the inconvenience is avoided which accompanies the 45 hitherto employed activating methods in which the liquid to be activated is brought into direct contact with the radioactive body producing emanations, said inconvenience consisting in that the said body thereby is 50 easily affected so as to be lost by and by. For instance, in radioactivating water by radioactive substance brought into direct contact therewith, part of said substance is always dissolved and thus lost and also being 55 fouls the water. In activating air by causing it to bubble up through a solution of a

radium salt, impurities present in the air, for instance small traces of sulfuric acid, will precipitate an insoluble salt in the radium solution, said salt being far less capable of yielding emanations than the solution, whence a constant degree of activation of the air cannot be obtained. The same will be the case with water activated with a material producing emanations, the quantity of said material being successively diminished by dissolution through the influence of the material to be activated. 60

As an example of applying the invention to the activation of liquids a method may 65 here be stated for producing radio-active (holding radium emanations) water by means of a radium salt in solid or dissolved form and with paraffin as a medium. The radium salt is incorporated or inclosed in a 70 sufficient quantity of paraffin for protecting it from direct contact with the water, said paraffin being melted for this purpose and then molded for instance into the shape of a ball. The activating substance thus obtained is then introduced (for instance in a 75 frame of silver wire) into the water to be made radioactive which should be contained in a vessel adapted to be closed for avoiding loss of emanation. 80

On the accompanying drawing such an activating substance is illustrated in cross section.

a is the radium salt, *b* the ball shaped coating of paraffin, and *c* a basket shaped 90 frame of silver wire.

By suitably regulating the quantity of radium salt in the activating substance thus prepared and the time for its contact with the water the latter can be activated to any 95 desired strength, *i. e.* acquire the desired quantity of radium emanations. The emanation produced by the radium is then absorbed by the paraffin oil which again yields it to the water in contacting therewith. The 100 quantity of paraffin oil (as that of paraffin in the previous example) should not be greater than is required for well inclosing and protecting the radium salt, as otherwise a too high quantity of emanations will remain in the oil without any use for the water. 105

Other liquids than water, as milk, beer, juices, etc., can be activated in the same way as that described for water. 110

In activating gases these need only be brought into contact with (for instance

led around) an activating substance with a strength depending upon the desired degree of activation; if the medium of the activating substance consists of a liquid, the gas 5 can be caused to bubble through the said substance, the emanation then being transferred into the gas.

The air coming from the activation apparatus of course also can be used directly for 10 inhalation, for instance by means of an inhalation mask, in which case it of course obtains the desired quantity of emanations by being exposed to the influence of the activating substance during a suitable space 15 of time.

As it sometimes may be advantageous to have the possibility of observing if there is activating substance present in a vessel, the said substance may be made self-luminous 20 by mixing into it bodies becoming fluorescent in radioactive radiation, as for instance sulfid of zinc, barium-platinocyanid. These substances are then mixed into the medium in the same way as the radioactive bodies 25 producing emanations and preferably simultaneously with these.

Having now particularly described the nature of my invention and the manner of its operation, what I claim is:

30 1. Improved radioactivating substances

for liquids and gases, consisting of an emanation producing material inclosed in a non-porous medium, indifferent in respect to the radioactive material as well as the medium to be activated and further possessing the 35 property of absorbing the emanation in its mass and allowing it to pass only through the said mass into the medium to be activated, the radioactive material being thus completely protected.

2. Improved radioactivating substances 40 for liquids and gases, consisting of an emanation producing radioactive material inclosed in a non-porous medium indifferent in respect to the radioactive material as well 45 as the medium to be activated and further possessing the property of absorbing the emanation in its mass and allow it to pass only through said mass into the material to be activated, the said non-porous medium 50 being coated with a body, becoming fluorescent in radioactive radiation.

In testimony whereof I have signed my name to this specification in the presence of two subscribing witnesses.

JOHN LANDIN.
